US00D479211S

(12) **United States Design Patent** (10) Patent No.: **US D479,211 S**
 Siddoway et al. (45) Date of Patent: ** Sep. 2, 2003

(54) **PORTABLE COMMUNICATION DEVICE**

(75) Inventors: **Craig F Siddoway**, Davie, FL (US);
Bruce A. Claxton, Coral Springs, FL (US); **Brian H. Philips**, Pembroke Pines, FL (US); **William H. Robertson, Jr.**, Ft. Lauderdale, FL (US)

(73) Assignee: **Motorola, Inc.**, Schaumburg, IL (US)

(**) Term: **14 Years**

(21) Appl. No.: **29/161,997**

(22) Filed: **Jun. 7, 2002**

(51) LOC (7) Cl. **14-03**

(52) U.S. Cl. **D14/137**

(58) Field of Search D14/137, 138, D14/218, 147-149, 247-249, 144, 240, 242, 341-347, 399, 426, 387, 429, 453, 197, 198, 189, 192, 193, 157, 194, 195, 196, 158; 379/433.01-433.13, 434, 419, 420.01-420.04, 428.01-428.02, 440; 455/550.01-90.3; D13/168; D18/2, 7; D21/517, 329, 331, 333; D10/104, 106, 65; 381/86
